(57) **CLAIM**

The ornamental design for a smart wearable band as shown and described.

DESCRIPTION

FIG. 1 is a top, right side perspective view of a smart wearable band of the new design.

FIG. 2 is front elevation view thereof.

FIG. 3 is a left side elevation view thereof.

FIG. 4 is a right side elevation view thereof.

FIG. 5 is a rear elevation view thereof.

FIG. 6 is a top plan view thereof.

FIG. 7 is a bottom view thereof; and,

FIG. 8 is a top elevation view thereof, showing the smart wearable band in a state of use.

The dashed broken lines illustrate portions of the smart wearable band and form no part of the claimed design. The dashed broken lines in FIG. 8 showing a hand represent environmental subject matter only and form no part of the claimed design.

1 Claim, 4 Drawing Sheets
